UNITED STATES PATENT OFFICE.

FRANKLIN O. FRASHER, OF PETERSBURG, DELAWARE.

HOLDBACK ATTACHMENT FOR VEHICLES.

SPECIFICATION forming part of Letters Patent No. 499,980, dated June 20, 1893.

Application filed March 21, 1893. Serial No. 467,046. (No model.)

To all whom it may concern:

Be it known that I, FRANKLIN O. FRASHER, a citizen of the United States, residing at Petersburg, in the county of Kent and State 5 of Delaware, have invented new and useful Improvements in Holdback Attachments for Thills, of which the following is a specification.

This invention relates to that type of hold- 10 back attachments for thills wherein a metallic frame or bracket attached to the thill is provided with a longitudinal slot which at one extremity is enlarged laterally to permit the escape of the head of a loop or eye to 15 which the breeching-strap is attached, if the animal passes from between the thills. In prior constructions of this character the slot is closed at each end and consequently it is impossible to arrange the frame or bracket at 20 the under side of the thill, as if arranged in this manner it is impossible for the loop or eye to automatically free itself from the frame or bracket. For this reason the prior constructions are only applicable to the in- 25 nner sides of the thills, which is objectionable for several reasons, chiefly because laterally projecting parts are present at the inner sides of the thills which are liable to injure the animal, and further because of the 30 uncertainty of the loop or eye becoming automatically disengaged when the animal passes from between the thills.

The objects of my invention are to avoid the objections stated; to provide a novel construction whereby the metallic frame or bracket 35 can be applied to the under side of the thill, with absolute certainty of the loop or eye becoming disengaged therefrom the instant the animal passes from between the thills; to 40 provide novel means for preventing accidental disengagement of the loop or eye from the frame or bracket, and to provide an improved construction wherein the eye or loop is adapted to lie close to the under side of the thill 45 and thus reduce the danger of breaking the parts if excessive strain is brought to bear thereupon in holding back a vehicle.

To accomplish all these objects my invention involves the features of construction

and the combination or arrangement of parts 50 hereinafter described and claimed, reference being made to the accompanying drawings, in which—

Figure 1, is a perspective view of my im- 55 proved hold-back attachment, a broken portion of the thill being exhibited. Fig. 2, is a bottom plan view of the same, showing the eye or loop in its normal position. Fig. 3, is a bottom plan view, omitting the lower plate of 60 the metallic frame or bracket. Fig. 4, is a similar view showing the position of the loop or eye in the act of passing from the frame or bracket, and Fig. 5, is a detail longitudinal sectional view of the hold-back attachment.

In order to enable those skilled in the art 65 to make and use my invention I will now describe the same in detail, referring to the drawings wherein—

The numeral 1 indicates a portion of a thill 70 to the under side of which my improved hold-back attachment is applied, as will be understood by reference to Fig. 1. The frame or bracket of the hold-back attachment comprises a base-plate 2, having longitudinal side flanges 3, which embrace and lie closely against the 75 sides of the thill, and a cap-plate 4 secured to the underside of the base-plate, preferably by the screws 5, which serve to secure the base-plate to the under side of the thill. The base-plate is formed with a recess 2^a, having under- 80 cut edges 6, Figs. 1 and 5, and the cap-plate contains a diagonal opening 7, Fig. 2, which recess and opening constitute a slot closed at the rear and open at the front for the free 85 escape of the loop or eye 8, to which the breeching strap is connected. The loop or eye lies approximately horizontal in a plane parallel with the under side of the thill, and it is provided with a head, formed, as here 90 shown, of a disk 9, connected with the loop or eye proper by a short shank 10, whereby the loop or eye lies close to the under side of the thill, thus reducing the downward pull on the loop or eye in holding back, and materially increasing the strength, durability, efficiency and usefulness of the device in practical 95 operation.

The edge 12 of the disk 9 is beveled, to ac-

commodate it to the under-cut edges 6, of the recess in the base-plate, so that when the loop or eye is in position for holding back a vehicle, the downward strain on the loop or eye 5 is counteracted by the co-acting edges 6 and 12, and likewise strain or pressure is removed from the cap-plate 4. In the construction described and shown the entire strain in holding back is thrown upon the base-plate at the 10 closed end of the slot, which slot, as before stated, is composed of the recess in the base-plate and the opening 7 in the cap-plate.

The normal position of the loop or eye in holding back a vehicle, is represented in 15 Figs. 1 and 2. In practice, the breeching-strap is connected with the loop or eye, preferably by a snap hook, and so long as the animal remains properly between the thills, the loop or eye will stand approximately 20 in such position as to be pulled rearward against the closed end of the slot. If, however, the animal should pass from between the thills, the loop or eye will turn and the head or disk 9 will rotate and then the forward pull of the breeching strap will move 25 the loop or eye forward, as indicated by the arrow Fig. 4, thereby pulling the loop or eye out of the open end of the slot in a plane parallel with the under side of the thill. This 30 is a very important feature of my invention and distinguishes it from prior constructions, in that I am enabled to apply the slotted frame or bracket to the under side of the thill, thus materially reducing the laterally 35 projecting parts, and placing the loop or eye in such position that it can lie approximately horizontal in a plane parallel with the under side of the thill. The construction also renders it possible to bring the loop or eye closer 40 to the under side of the thill, which is a very desirable feature.

To prevent accidental disengagement of the loop or eye from the frame or bracket, I provide the latter with a spring-pressed dog 45 13, pivoted as at 14, between the base-plate and the cap-plate, and acted upon by a flat spring 15, which is secured in place by a rivet or pin 16, passing through the cap-plate and base-plate. The spring-pressed dog, when 50 the parts are in normal position, lies in front of a cut-away part of the head or disk 9, and prevents the latter being accidentally moved out through the slot of the frame or bracket. If the loop or eye be turned to project forward, 55 for example as in Fig. 4, the spring-pressed dog will bear against the beveled periphery of the head or disk and the friction between the parts will be sufficient to prevent accidental disengagement of the loop or eye from the 60 frame or bracket. As here shown, the dog 13 and spring 15 lie in a slotted part of the cap-plate, and the dog and spring are protected by the cap-plate and base-plate, as will be understood by reference to Figs. 1 and 3.

65 The head or disk 9 is substantially flat and has a flat bearing against the base-plate,

whereby the loop or eye is steadied in its movements and the head or disk cannot rock in a vertical plane.

The flattened surface of the base-plate, between the side flanges 3, adapts it to the flattened under side of the thill.

Having thus described my invention, what I claim is—

1. A hold-back attachment, consisting of a frame adapted to be secured to the under side of a thill and composed of a base-plate and a cap-plate having respectively a recess and an opening to form a slot which opens at the front end of said parts, and a loop having a flat head or disk rotatable between the base-plate and cap-plate and adapted to pull out of the open end of the slot in a plane parallel with the under side of the thill, substantially as described. 85

2. A hold-back attachment, consisting of a frame adapted to be secured to the under side of a thill and having a slot which opens at the front end of the frame, a loop having a head rotatable in the frame and adapted to pull out of the open end of the slot in a plane parallel with the under side of the thill, and a spring-pressed dog acting against the rotatable head of the loop to prevent accidental disengagement of the latter from the frame, 95 substantially as described.

3. A hold-back attachment, consisting of a frame adapted to be secured to the under side of a thill and composed of a base-plate and a cap-plate having respectively a recess and an opening to form a slot which opens at the front end of said parts, a loop or eye having a head or disk rotatable between the base-plate and cap-plate and adapted to pull out of the open end of the slot in a plane parallel 105 with the under side of the thill, and a spring-pressed dog pivoted between the base-plate and cap-plate for acting against the periphery of the head or disk to prevent its accidental movement out of the slot, substantially 110 as described.

4. A hold-back attachment, consisting of a frame adapted to be secured to the under side of a thill and having a slot which opens at the front end of the frame, a loop or eye lying approximately horizontal in a plane parallel with the under side of the thill and having a flat head or disk which bears flatly against the frame and is adapted to rotate and move out of the open end of the slot in a plane parallel with the under side of the thill, a dog pivoted to the frame and arranged to bear against the periphery of the rotatable head or disk to prevent accidental movement of the latter out of the open end of the slot, 125 and a spring acting against the dog to press it inwardly against said head or disk, substantially as described.

5. A hold-back attachment, consisting of a frame or bracket having under-cut edges 6, 130 and a slot open at its front end, a loop or eye having a head or disk 9 provided with a bevel

bevelled edge 12, adapted to rotate in the frame or bracket, a dog pivoted to the frame or bracket and arranged to bear against the bevelled edge of the head or disk, and a spring 5 acting upon the dog to press it inwardly, substantially as described.

In testimony whereof I have hereunto set

my hand in presence of two subscribing witnesses.

FRANKLIN O. FRASHER.
